DISCRETE POSITIONING MECHANISM

Marshall E. Freeman, San Jose, Calif., assignor to International Business Machines Corporation, New York, N.Y., a corporation of New York

Filed June 25, 1959, Ser. No. 822,963

6 Claims. (Cl. 121—38)

This invention relates in general to positioning devices, and in particular to pressure responsive devices for positioning a member at a selected one of a plurality of discrete positions.

The prior art has suggested various arrangements for positioning a member selectively at one of a plurality of discrete positions. In one known arrangement referred to in the art as a cylinder adder, a number of conventional cylinder-piston units are arranged so that each cylinder may be supplied with fluid pressure to move its associated piston between a pair of stops separated a predetermined distance. Usually in these arrangements the predetermined distance between stops for each unit is different forming, for example, a mathematical progression such as 1, 2, 4 and 8. By connecting each piston with the adjacent cylinder and the member to be positioned to the last piston, it will be seen that any one of a plurality of positions may be obtained merely by selectively actuating the units in various combinations.

With conventional cylinder-piston units it is desirable to make the piston land correspond substantially to the diameter of the piston in order to prevent the piston from cocking in the cylinder. Also, a piston rod is usually employed to transmit the motion of the piston to the adjacent cylinder, the rod having one end integral with the piston and suitably attached to the adjacent cylinder. The length of the rod and the piston land therefore determine to a great extent the minimum size to which the unit may be manufactured.

Additionally, when conventional cylinder-piston units are employed to position a member to selected locations which are closely spaced, for example, twenty mils apart, the tolerances involved in machining conventional piston cylinders become quite close. As a result the cost of a conventional cylinder-piston unit increases when the distance between positions decreases.

Further, since the motion of one cylinder-piston unit is transmitted to the adjacent unit through the piston rod, considerable care must be exercised when the individual units are arranged together to insure that they act along a common axis. Otherwise the units tend to bind and do not function properly.

It has been found in accordance with the present invention that the above-mentioned disadvantages may be overcome by providing a cylinder-type adder wherein the motion of one unit is transmitted to the adjacent unit by means of a ball, the motion transmitting ability or the distance through which the adjacent unit is moved being determined by the distance that the ball protrudes from the end of the cylinder or capsule in which it is mounted as the ball is forced onto a conical seat by fluid pressure supplied to the capsule.

It is therefore an object of the present invention to provide an improved mechanism for positioning a member selectively to any one of a plurality of discrete positions.

Another object of the present invention is to provide a compact cylinder adder type positioning mechanism.

2

A further object of the present invention is to provide a cylinder adder type mechanism for selectively positioning a member to any one of a plurality of closely spaced locations wherein the manufacturing tolerances of the mechanism are minimized.

A still further object of the present invention is to provide a cylinder adder type positioning mechanism wherein the individual units are not required to act along a linear axis.

10 The foregoing and other objects, features and advantages of the invention will be apparent from the following more particular description of preferred embodiments of the invention, as illustrated in the accompanying drawings.

In the drawings:

15 Fig. 1 is an enlarged view, partly in section, of a cylinder adder type positioning mechanism embodying the present invention;

Fig. 2 is an enlarged perspective view, partly in section, of one of the capsule units employed in the mechanism

20 shown in Fig. 1;

Fig. 3 is a view similar to Fig. 1 illustrating the positioning mechanism in an actuated position; and

Fig. 4 is a view similar to Fig. 1 illustrating a modification of the positioning mechanism shown in Fig. 1.

25 Referring to the drawings, and particularly to Fig. 1, the positioning mechanism comprises generally a plurality of movable capsule units 10, an output piston member 11 for transmitting the accumulated movement of the capsule units 10 to an output member indicated schematically as a pointer 13, which is to be selectively positioned at any one of the positions 14 indicated on the scale 15. The capsule 10 and the piston member 11 are mounted for sliding movement in a suitable housing 16.

30 The capsule units 10 are similar so only one is described in detail. With reference to Fig. 2, each capsule unit 10 comprises a cylinder member 23, a hardened precision ball 24, and a cover 25 suitably secured to one end of the cylinder member 23. The other end 26 is provided with a seat 27 for receiving the precision

35 ball 24, the curved line of contact 27L therebetween defining a first reference plane. The seat 27 may be circular but preferably has a conical or spherical shape as shown in the drawing. The distance "D" from the line of contact 27L of the ball 24 and the conical seat 27

40 to the reference surface 28 in effect determines the distance "X" in Fig. 3 that the precision ball 24 protrudes from the unit 10. As shown in Figs. 1 and 3 the capsule units 10 are identical except for the distance "X." In this instance the "X" distances form a mathematical progression of 1, 2, 4 and 5 which allows the pointer 13 to be positioned at any one of the thirteen positions 0 through 12 of the scale 15.

45 In practice the distance "X" is controlled quite accurately by controlling the distance "D." Distance "D" is controlled by first providing the conical seat 27 and then machining the end 26 of the cylinder 23 until the distance "X" that the ball protrudes past the machined reference surface 28 corresponds to the desired distance.

50 Since hardened precision steel balls may be obtained 60 economically with tolerances of $\pm 2 \times 10^{-6}$ and milling operations to tolerances of ± 1 mil are also quite economical to obtain, the fabrication of the capsule units 10 are relatively inexpensive for discrete positioning devices where the motion transmitting ability of the smallest unit is in the vicinity of 20 mils.

55 Referring again to Fig. 1, means are further provided for supplying fluid pressure selectively to each of the capsule units 10. This means, as shown, comprises a pump 31 having a pressure supply conduit 32 and a return conduit 33 which are selectively connected to supply ports 34a through 34d in the housing 16 through four separate three-way valves 35a through 35d which

are illustrated schematically in the drawing. If desired the valves 35 may be actuated by means of solenoids (not shown) which are energized by a binary coded signal corresponding to the desired positions 14 of pointers 13.

The positioning mechanism further includes means 37 for biasing the capsule units to a home position. As shown in Fig. 1 this means comprises the piston member 11 which is disposed at the output end of the housing 16 and supplied with a constant fluid pressure from a suitable valve 38 connected to the pressure supply conduit 32 of the pump 31. Other suitable biasing means known in the art may be employed if desired. Similarly, the positioning mechanism shown in Fig. 1 may also be provided with suitable shock absorbing means 39. As shown this shock absorbing means 39 comprises a capsule unit 40 similar to the capsule units 10. Capsule unit 40 is supplied with constant pressure from pressure supply conduit 32 through valve 41 and port 34e, this pressure being slightly greater than the biasing pressure supplied to the piston member 11.

Assuming that the capsule units 10 are in the position shown in Fig. 1 wherein the valves 35 are positioned to connect each unit 10 to the return conduit 33 of the pump 31, that suitable pressures are supplied to the biasing means 37 and the shock absorbing means 39, and that it is desired to position the pointer 13 to position 7 on scale 15, the operation of the mechanism is as follows. Valves 34a, 34b, and 34c are actuated to the position shown in Fig. 3 which causes capsule units 10a through 10c to be supplied with pressure. The precision ball 24 of capsule 10a is moved to the conical seat 27 and protrudes past reference edge 28 the predetermined distance "X" corresponding to the distance between scale positions 14 on the scale 15. Similarly the precision ball 24 of capsule 10b is moved to its conical seat 27 and protrudes past its reference edge 28, a distance corresponding to two full scale positions. Likewise the precision ball 24 of unit 10c extends past its reference edge 28 a distance corresponding to four scale divisions. The total displacement of the piston member 11 and the pointer 13 therefore corresponds to the sum of the individual displacements of the capsules. It will thus be seen that any of the twelve positions on the scale 15 may be obtained merely by actuating the valves 35 in various combinations.

Fig. 4 illustrates a modification of the positioning mechanism shown in Fig. 1, and the same reference numerals have been employed to designate identical parts. In the embodiment shown in Fig. 4 the piston member 11 of Fig. 1, which serves the dual function of biasing the capsule units 10 to a home position and of transmitting the accumulated motion of the individual capsules 10 to the pointer 13, has been eliminated by reversing the position of each of the capsules 10 relative to their position in Fig. 1 and by modifying the end capsule 10d. As shown in Fig. 4 the end capsule 10d' is provided with a rod 44 which extends through the housing 16 to the pointer 13. Capsule 10d' therefore performs the same function as the piston member 11 but allows the length of the mechanism to be further reduced. The operation of the mechanism shown in Fig. 4 is identical to that shown in Fig. 1.

While the invention has been particularly shown and described with reference to preferred embodiments thereof, it will be understood by those skilled in the art that various changes in form and details may be made therein without departing from the spirit and scope of the invention.

What is claimed is:

1. A mechanism for selectively positioning an element to any one of a plurality of discrete positions comprising: a plurality of capsule units, a housing mounting said units in serial motion transmitting relationship, biasing means disposed in said housing urging said units to a home

position wherein adjacent units are in contact, a ball disposed for rolling engagement in each capsule unit and arranged to protrude past an open end of said unit a predetermined distance to move succeeding units a corresponding amount, pressure supply means connected to each unit, means for controlling said supply means to cause selective movement of each said ball to a protruded position, and means mounted for movement with the last capsule unit for transmitting the cumulative motion of said units to said element.

2. A mechanism for selectively positioning an element to any one of a plurality of discrete positions comprising: a plurality of capsule units, a housing mounting said units in serial motion transmitting relationship, biasing means disposed in said housing urging said units to a home position wherein adjacent units are in contact, a ball disposed for rolling engagement in each capsule unit and arranged to protrude past an open end of said unit a predetermined distance to move succeeding units a corresponding amount in response to fluid pressure supplied to said capsule unit, pressure supply means connected to each unit, means for controlling said supply means to cause selective movement of each said ball to a protruded position, and means mounted in motion transmitting relationship between said biasing means and said element for transmitting the cumulative motion of said units to said element.

3. The combination recited in claim 2 wherein said capsule units are identical except for their length.

4. The combination recited in claim 2 further comprising means disposed in said housing for absorbing impact shocks between adjacent units.

5. A mechanism for selectively positioning an element to any one of a plurality of discrete positions comprising: a plurality of capsule units each having a cylindrical bore one end of which is closed and the other end of which is open, a housing mounting said units in serial motion transmitting relationship with the axis of said bores disposed along a path, biasing means disposed in said housing for urging said units to a home position wherein adjacent units are in contact and for maintaining said units in motion transmitting relationship relative to each other, means mounted for movement with the last capsule unit for transmitting the cumulative motion of said units to said element, a ball disposed in rolling engagement with the cylindrical bore of each capsule unit and arranged to protrude past the open end of said unit to move the succeeding units a predetermined distance corresponding to a predetermined multiple of the spacing between adjacent said discrete positions in response to fluid pressure supplied selectively to said capsule units, each unit including a pair of reference planes normal to the axis of said bore to determine the movement imparted to succeeding units by a selected unit, a seat presenting a circular line of contact disposed in one of said reference planes for receiving said ball when said unit is pressurized, an accurate surface at the open end of said unit defining the other reference plane, and means for supplying fluid pressure to each of said units selectively whereby said element is moved to one of said discrete positions.

6. A mechanism for positioning an element to any one of a plurality of discrete positions comprising: a plurality of capsule units, each of said units including a capsule having a closed end and an open end, a cylindrical bore extending therebetween, a ball disposed in said bore in rolling engagement with the cylindrical surface of said bore, means for supplying pressure to said bore to move said ball to said open end, a conical seat disposed at said open end coaxially with said bore for receiving said ball, the line of contact therebetween defining a first reference plane, said seat having a diameter relative to said ball to allow a portion of said ball to extend past said first reference plane a predetermined amount, and an accurate reference surface on the open end of said

capsule disposed in a second reference plane normal to the axis of said bore and spaced axially from said first reference plane a distance determined by the spacing of said discrete positions, means mounting said capsule units in series along a path in cumulative motion transmitting relationship with the accurate surface of one capsule unit adjacent the closed end of the succeeding unit, means biasing said capsule units to home position wherein said adjacent units are in contact, means for transmitting the movement of said capsules to said element, and means for selectively controlling the pressure supply means of

each said unit whereby said element is moved to one of said discrete positions in accordance with the cumulative movement of said capsule units.
